UNITED STATES PATENT OFFICE.

CHARLES W. BUCKLEY, OF PHILADELPHIA, PENNSYLVANIA, ASSIGNOR TO
JOHN A. BRILL, OF SAME PLACE.

SAND-DISTRIBUTUTING APPARATUS.

SPECIFICATION forming part of Letters Patent No. 559,671, dated May 5, 1896.

Application filed September 25, 1895. Serial No. 563,612. (No model.)

To all whom it may concern:

Be it known that I, CHARLES W. BUCKLEY, a citizen of the United States, residing at Philadelphia, in the county of Philadelphia and State of Pennsylvania, have invented certain new and useful Improvements in Sand-Distributing Apparatus, of which the following is a specification.

The object of my invention is to provide improved means for depositing the desired quantity of sand upon a track-rail to increase the traction of the car-wheels thereon.

The invention consists in a novel arrangement of valve mechanism to be used in connection with a hopper or sand-receptacle, the valve being so arranged that when opened it will allow the delivery of sand, but when closed will prevent the escape of any particles of sand.

To this end the invention comprises a hopper or sand-receptacle, a valve box or receptacle beneath it, and a valve consisting of an oscillatory plate closing the lower opening of said box and having a coupling for connection with a delivery-pipe. Means are also provided for holding said plate in such position that said coupling will normally be out of line with the opening in said valve-box and other means for operating said plate at will to allow the escape of sand.

The invention also consists in means for directing the delivery of sand upon the car-rail at all times and under varying conditions.

The invention also consists in the novel details of improvement and the combinations of parts that will be more fully hereinafter set forth, and then pointed out in the claims.

Reference is to be had to the accompanying drawings, forming part hereof, wherein—

Figure 1 is a partly sectional side elevation of a portion of a car, showing my improvements in position thereon. Fig. 2 is a plan view, enlarged, of the improved valve mechanism. Fig. 3 is a side elevation thereof, and Fig. 4 is an under side view thereof.

In the accompanying drawings, in which similar numerals of reference indicate corresponding parts in the several views, the number 1 indicates the car-body, 2 is its floor, 3

is the platform, 4 is the dashboard, 5 is the platform-knee, and 6 is a sill, all of which may be of suitable construction.

7 is a hopper or other suitable sand-receptacle carried within the car on its floor 2, 55 said hopper or receptacle 7 having a lower opening for the exit of the sand, said opening leading to my improved valve-box 8, as in Fig. 1.

The upper end of the valve-box 8 fits in an 60 opening 2^a in the floor 2, and for simplicity and convenience of attachment said box is provided with side lugs 9 9, which are below the upper surface of the box, so as to rest against the under surface of the floor 2, while 65 the upper edge of said box comes about flush with the top of said floor, said lugs being bolted or screwed to the floor. Three of such lugs 9 are shown, which allow one side of the valve-box 8 to come flush with the side wall of 70 the car.

The valve arrangement is constructed as follows: Around the upper edge of the central opening of the box 8 is an upwardly-extending flange 10, which passes into the lower 75 opening of the hopper or receptacle 7 to make a tight fit for the latter. (See Fig. 1.) The central opening of the box 8 is preferably rectangular, and in order to properly guide the sand to the lower outlet the sides and corners 80 of said opening are beveled inwardly and downwardly, two corners having triangular projecting walls 11, which are joined by an intermediate triangular wall 12. The wall 13 is downwardly extending, having a rounded lower edge; but the interior of the box 8 85 may be arranged in suitable manner.

The box 8 at its lower part has a plate or frame 14, which extends outwardly, as in Fig. 2, having two sides 15, arranged at an acute 90 angle, and the side 16, arranged in the arc of a circle described around a pivot 17.

18 is a valve-plate which substantially corresponds in outline to the plate 14, and it is hung on the pivot 17 so as to oscillate thereon, the outer edge 19 of plate 18 being curved to correspond to the curve 16 of plate 14, being held and guided close beneath the plate 14 by guide-lugs 20, carried by the plate 14. (See Figs. 1 and 3.)

The plates 14 and 18 extend parallel to the car-floor, so that the plate 18 can oscillate on a horizontal plane beneath the box 8.

The plate 18 carries one or more upwardly-projecting stirring-fingers 18^a, which project through the box 8 into the hopper to stir the sand as the plate 18 is operated.

The plate 18 has an opening 21, which aligns with a coupling or tube 22, that is rigidly attached to said plate.

At 23 is an annular rib on the coupling 22, and 24 is a flexible hose or pipe, which at its upper end fits over the coupling 22, the rib 23 serving to assist in holding said hose on said coupling. (See Fig. 1.) In the normal position of the plate 18 its opening 21 and the coupling 22 are out of line with the opening in the bottom of the box 8, and when it is desired to drop sand the plate 18 is drawn around to align its opening 21 with the opening in the bottom of the box. For this purpose I have shown a jaw or lugs 25 on the bottom of the plate 18, to which jaw or lugs the inner end of a connecting-rod 26 is pivoted. The rod 25 extends forwardly under the car floor and platform and is pivoted to an operating lever or bar 27, which is shown pivoted on the platform 3 and extended up by the dashboard 4 in convenient position for operation by the motorman or gripman.

The plate 18 is held in the normally-closed position by means of a suitably-arranged spring. I have shown a spring 28, which is coiled on a rod 29, that is curved on the arc of circle described around the pivot 17, said rod being supported by lugs 30 and 31, depending from the plate 14. The lug 30 passes through an opening 32 in the plate 18, so that said plate can have free oscillatory movement. (See Fig. 4.) The plate 18 carries a lug 33, which has an opening to receive the rod 29, so that said lug can slide along said rod as the plate 18 turns on its pivot, and the spring 28 bears at one end against the lug 30 and at its other end against the lug 33, the tendency of the spring 28 being to keep the plate 18 in the normally-closed position and to return it to said position after the plate 18 has been operated by the lever or bar 27.

The hose or tube 24, which is preferably flexible, allows of the various movements of the plate 18, and the tube 24 at its lower end is guided to lie over the rail 34 by a suitable guide-bar 35 carried by the car. This guide-bar 35 has at one end an opening for the passage of the hose or tube 24, said guide-bar extending down near the rail 34 to properly guide the lower end of the hose or tube 24. The guide-bar 35 is shown bolted at its upper end to a cross-beam 36 of the car, and said bar is also preferably made adjustable for adjusting the end of the hose or tube 24 in different positions. For this purpose the guide-bar 35 may be made in two parts 35^a and 35^b, jointed together at 37, the part 35^a having a horizontal bend 35^c to hold the part 35^b and pivot-bolt 37. By adjusting the part 35^b

laterally and securing it by the pivot-bolt 37 the lower end of the hose or tube 24 can be properly adjusted over the car-rail 34.

Having now described my invention, what I claim is—

1. The combination with a hopper, of a sand-box having an open bottom, and a plate oscillating horizontally beneath said opening, said plate being provided with an aperture and a chute, substantially as described.

2. The combination with a hopper, of a sand-box having an open bottom, and a plate oscillating horizontally beneath said opening in a direction substantially parallel with the line of travel of the car, said plate being provided with an aperture and a chute leading therefrom, substantially as described.

3. The combination of the valve-box having an open bottom and the plate having an aperture and chute and moving across said bottom of the valve-box, said box having sloping sides the upper edges of which are straight and parallel, while the lower edges are concave and convex arcs of a circle, whereby the bottom of said valve-box is curved and of substantially uniform width, substantially as described.

4. In a sanding device, the combination of a valve-box having an open bottom and an outwardly-extending plate level with its bottom, and a plate hinged thereto carrying a chute, and adapted to close the bottom of the valve-box, said latter plate being provided with an aperture and a chute, substantially as described.

5. In a sanding device, the combination of a valve-box having an open bottom and an outwardly-extending plate level with its bottom, and a plate hinged thereto so as to move across the open bottom of the valve-box, one of said plates having a rounded edge to serve as a guide and the other having lugs turned over said edge and holding the plates together, substantially as described.

6. In a sanding device, the combination of the plate 15 having the lug 30, and the apertured movable plate 18, having lug 31, one of said lugs being apertured, curved rod sliding in one of said lugs and supported by the other, and spring around the rod, substantially as described.

7. A valve-box having a plate 14 provided with lugs 30 and 31, and a curved rod 29 carried by said lugs, with a plate 18 pivotally carried by the plate 14, means for supporting the outer edge of said plate 18, a lug 33 carried by the plate 18 and receiving the rod 29, and a spring coiled on the rod 29 and bearing at one end against the lug 30 and at its other end against the lug 33, the plate 18 having a jaw, a rod connected with said jaw, and an operating-lever to actuate said rod, as and for the purposes specified.

8. A valve-box having an opening combined with an oscillatory plate pivotally connected with said box and having an aperture and a coupling secured to and movable with said

plate and alined with said aperture, and with a rod connected with said plate, and means connected with said rod to operate the latter, substantially as described.

- 5 9. The combination of a car, with a hopper or sand-box, a valve-box alined therewith and carried by the car, a pivoted plate having an aperture and a coupling secured to and movable with said plate and alined with 10 said aperture, a spring to hold and actuate said plate, a rod connected with said plate, a lever to operate said rod, and a hose or tube connected with said coupling, substantially as described.

10. The combination of a sand receptacle 15 and a valve, with an oscillatory chute and a guide for the same comprising a depending bar having a horizontal elbow, and a horizontally-swinging arm for the chute extending from said elbow, substantially as described. 20

Signed at Philadelphia, in the county of Philadelphia and State of Pennsylvania, this 21st day of September, 1895.

CHARLES W. BUCKLEY.
